CLAIM

The ornamental design for an exhibit display, as shown.

DESCRIPTION

FIG. 1 is a perspective view of an exhibit display showing a new design;

FIG. 2 is a front elevational view thereof;

FIG. 3 is a right side view thereof;

FIG. 4 is a left side view thereof;

FIG. 5 is a rear elevational view thereof;

FIG. 6 is a top plan view thereof;

FIG. 7 is a perspective view of a second embodiment of an exhibit display showing a new design;

FIG. 8 is a front elevational view of the second embodiment;

FIG. 9 is a right side view of the second embodiment;

FIG. 10 is a left side view of the second embodiment;

FIG. 11 is a back elevational view of the second embodiment; and,

FIG. 12 is a top plan view of the second embodiment.

The supports in FIGS. 8-11 have the same length as shown in FIG. 7, but are shown broken away for ease of disclosure on the drawing sheet.

In the drawings, the broken lines represent environmental structure forming no part of the claim.
